UNITED STATES PATENT OFFICE.

GUIDO G. BEHN, OF DETROIT, MICHIGAN.

METHOD OF MAKING HOOD HINGES FOR AUTOMOBILES.

Original application filed July 3, 1920, Serial No. 393,797. Divided and this application filed October 8, 1923. Serial No. 667,147.

To all whom it may concern:

Be it known that I, GUIDO G. BEHN, a citizen of the United States, residing at Detroit, county of Wayne, State of Michigan, have invented a certain new and Improved Method of Making Hood Hinges for Automobiles, of which the following is a specification, reference being had therein to the accompanying drawings.

10 My invention relates particularly to a method of making hood-hinges for automobiles, although it may be capable of use for other purposes.

As is well understood by those skilled in the manufacture of automobiles, difficulty has been experienced in the past in producing a hood-hinge which will withstand the rough use to which it is subjected and will not render the hood unsightly. Since the 20 hood is at all times directly in front of the driver's eye and is a part of the car to which attention is usually first directed, it is most important that it shall have a neat and pleasing appearance. Heretofore, it has been customary to use a line of rivets or a series of spot-welds parallel with the pintle of the hinge to secure the hinge to the adjacent parts of the hood, and these have interfered with finishing the hood, since the rivet 30 heads project, and the spot-welding leaves indentations or spots where the enamel does not adhere well.

My present invention obviates both of these objections and leaves a hood the entire 35 surface of which is unobstructed and can be perfectly finished.

The invention will be fully understood from the following description when taken in connection with the accompanying drawings, and the novel features thereof will be 40 pointed out and clearly defined in the claims at the close of this specification.

In the drawings, Fig. 1 is a side elevation of the hood of an automobile to which my 45 invention is applied.

Fig. 2 is a section on line 2 of Figure 1. Fig. 3 is a section of one hinge member ready to be secured to the hood.

Fig. 4 shows the hood and hinge member secured together.

Fig. 5 shows the parts shown in Figure 4 completed and ready to be assembled.

Referring now to the drawings, I first cut a suitable piece of sheet metal and form the same as shown in Figure 3 to form one hinge member. As will be seen, this hinge member 11 is somewhat U-shaped in cross section, having two legs *a* and *b* which collectively constitute the leaf portion of the hinge, and a cylindrical or tubular portion *c*, which is interrupted at intervals in the well-known manner. When the parts are assembled, the tubular portion receives the pintle 12. One hood member 13 is then bent to an angle to form a flange *d* along its edge, as shown in Figure 4, and it is then superposed in proper position on the hinge member with the flange *d* in contact with the leg *b* of the hinge member. The parts are then secured together in whatever manner is most convenient, as for instance, by spot-welding or riveting.

In the drawings, I have shown spot-welding at the points 14, 14. Spot-welding is convenient because it does not require any punching operation and secures both legs of the hinge and the flange of the hood together at a single operation. The parts are then in the position shown in Figure 4. Thereafter, the flange *d* of the hood member 13 is bent by rolling or otherwise to the position shown in Figure 5 in which the surfaces are practically in contact with each other and as nearly parallel as the nature of the material will permit.

The other hood member 15 and hinge member 16 are similarly constructed and secured together and the two hood members assembled by the insertion of the pintle 12.

When completed, the exterior surface of the hood is left entirely smooth and is not marred by any spot-welding or rivet heads, so that the enamel or paint can be applied uniformly to its entire surface and its surface can be rubbed and polished with perfect ease.

The hinge produced by the method above described forms the subject matter of a prior application filed July 3, 1920, Serial No. 393,797, of which this case is a division.

What I claim is—

1. The method of hinging automobile hood members and the like which consists in providing a hinge member having a tubular pin-

tle receiving portion and a leaf portion, securing an edge portion of a hood member to the outer side of the leaf portion of said hinge member, and then folding said hood member upon itself along a line parallel with and adjacent to the tubular portion of said hinge member.

5. 2. The method of hinging automobile hood members and the like which consists

in forming U-shaped hinge members, securing each hood member to the appropriate hinge member, and then folding the hood member upon itself along a line parallel with and adjacent to the folded edge of the U-shaped hinge member so that the junction 10 between said two members is concealed.

In testimony whereof I affix my signature.

GUIDO G. BEHN.
